(57) **CLAIM**

The ornamental design for a silicone breast pump stopper, as shown and described.

DESCRIPTION

FIG. 1 is a front elevational view of a silicone breast pump stopper showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a bottom, front and right side perspective view thereof.

The broken lines in the drawings illustrate portions of the silicone breast pump stopper which form no part of the claimed design.
